PISTON RING

Macy O. Teetor, Newcastle, Ind., assignor to The Perfect Circle Company, Hagerstown, Ind., a corporation of Indiana

Application February 18, 1939, Serial No. 257,082

7 Claims. (Cl. 309—45)

My invention relates to piston rings adapted to be mounted in the ring groove in a piston of an internal combustion engine having a cylinder wall to be engaged, and it has to do particularly with segmental rings of the foregoing character adapted for reducing oil consumption.

One of the objects of my invention is to provide an improved ring of the foregoing character which is of simple construction, is inexpensive to manufacture, and which is adapted to perform its intended functions in a highly efficient manner.

Another object is to provide an improved segmental ring which includes a pair of thin, flat, split, ring-like sections or rails that are spaced apart axially by a spring section or member which is adapted to expand the rails radially.

A further object is to provide an improved spring expander which takes the form of a one-piece, band-like spring member having certain portions with parallel side edges adapted to be disposed between and engage parallel facing sides of the rails for spacing them apart without exerting axial pressure thereon, and other portions adapted to engage the inner circumferential edges of the rails to expand them radially without affecting the axial position of the rails as provided by the spacing portions.

Other objects and advantages will become apparent as this description progresses and by reference to the drawings wherein—

Figure 1 is a horizontal section through the groove of a piston and illustrating ring structure embodying my invention mounted therein;

Fig. 2 is an enlarged sectional view of the structure shown in Fig. 1, the same being illustrated in operating relation to a cylinder wall;

Fig. 3 is an assembly view of the ring structure shown in Figs. 1 and 2; and

Fig. 4 is a fragmental, side elevational view of the ring structure shown in the previous figures, and further illustrating the manner of interlocking the ring expander sections.

The ring structure shown in the drawings is adapted to be mounted in a groove 10 (Figs. 1 and 2) in a piston 11 of an internal combustion engine having a cylinder 12 in which the piston operates. The piston may take any suitable form, and it is provided with an annular series of oil holes 13 leading through the piston wall from the bottom of the ring groove 10 for drainage of oil from the latter into the engine crank case (not shown). The ring structure shown is of segmental form, including a pair of rails 14, 15 (Figs. 2 and 3) and a spacer-expander section 16,

5 The rails or segments 14, 15 (Figs. 2 and 3) are of similar construction, each being formed from a thin, preferably steel, material to a flat, ring-like shape split at 17 for a purpose that will be well understood. Such rails are adapted to be disposed along the opposite sides of the ring groove 10 with their facing sides normally disposed in parallel relation. Also, the rails 14, 15 are of such width that, when they are installed in the ring groove 10 and the piston 11 is inserted in the cylinder 12, their thin outer peripheries engage the cylinder wall under some tension.

10 The spacer-expander section 16 takes the form of a band-like spring member of polygonal-like shape having side portions 18 joined at their ends by rounded or humped, spring-like portions 19. The expander section is of substantially the same width throughout as the ring structure so that it is confined between the rails 14, 15 and the bottom of the ring groove 10, with the humps 19 engaging the inner peripheries of the rails 14, 15 and acting as spring portions for expanding the rails radially toward the cylinder wall. The expander sides 18, adjacent their central portions, seat against the bottom of the ring groove 10, thereby supporting the expander section for the rail expanding action just described.

15 The expander section or spring member 16 also spaces apart the rails 14, 15 without exerting any axial expanding action thereon and without affecting the axial position of the rail sections as they are expanded radially. This spacing is accomplished by providing the spring member 16 with circumferentially spaced spacing portions 20 struck out or drawn or otherwise formed from the sides 18 thereof. These portions take the form of spacing humps 20 having parallel side edges 20a, which humps are of sufficiently reduced width to extend between the normally spaced rails 14, 15, with their side edges, which are parallel to the facing sides of the rails, engaging and spacing apart the rails without exerting axial expanding pressure thereon.

20 In the use of the structure above described, oil scraped from the cylinder wall is drained radially through the ring structure and back to the engine crank case through the piston holes 13 by passing over and under the rails 14, 15. The rails 14, 15 normally have sufficient clearance 25 with respect to the side walls of the ring groove 10 to permit oil collected between the rails to readily pass the structure under the influence of the hydraulic action that takes place in the operation of the structure, and by which there is a tendency for oil to be thrown, forced or pumped,

so to speak, toward the opposite side walls of the ring groove. Oil drainage past the expander section 16 may take place through the openings 21 formed in making the spacing humps or portions 20 or, if desired, additional circumferentially spaced openings may be formed in the spacer section, or the side edges thereof may be recessed to more readily permit passage of oil at those points.

It is desirable, for best operation of my ring structure, that the rail joints 17 and the joint 22 formed by the free ends 16^a and 16^b of the expander section 16 be maintained substantially in alignment with each other. To insure this relationship, and to avoid relative creepage of the sections during operation, I interlock the ends 16^a and 16^b of the expander section with the split ends of the rail sections. Specifically, the expander end portions 16^a and 16^b take the form of end parts 23 and 23^a bent radially outward and terminating in reversely bent parts 24 and 24^a. The reversely bent parts 24, 24^a are formed to the same width as the expander spacing portions 20, and the split end portions of the rails 14, 15 are adapted to seat thereon for axial support. The upper edge of the radial part 23^a of the right-hand end portion 16^b (Figs. 3 and 4) extends flush with the upper edge of the expander section, while the corresponding upper portion of the left-hand end part 23 is cut away to a point substantially in the same plane as the upper edge of the spacing portions 20. With this arrangement, the left-hand end of the upper rail 14 may pass the left-hand end part 23 to abut the right-hand end part 23^a, while the right-hand end of such upper rail cannot pass the right-hand end part 23^a. In this way, the right-hand end part 23^a is disposed in the joint of the upper rail 14 thereby preventing any material circumferential movement of the latter relative to the expander section. The lower edges of the expander end parts 23 and 23^a are formed similarly to the upper edge portions thereof except that they are reversed so that the lower edge of the right-hand end part 23^a is cut away to the level of the lower sides of the spacing portions 20 and the lower edge of the left-hand end part 23 is flush with the lower edge of the expander. Thusly, the lower rail 15 is interlocked with the left-hand expander end part 23 in the same manner as the upper rail 14 is interlocked with the right-hand end part 23^a.

I believe that the operation and advantages of my invention will be well understood from the foregoing description. The rails may be quite thin so that thin, outer edge portions or peripheries engage the cylinder wall. By spacing apart the rails with a one-piece spring expander, I provide a simple and inexpensive construction which is adapted to perform its intended functions in a highly efficient manner.

I claim:

1. A piston ring structure adapted for use in a ring groove in a piston of an internal combustion engine having a cylinder wall to be engaged, comprising a pair of thin, split rails having parallel sides adapted to be disposed along the opposite sides of the ring groove, and a spring expander of ribbon steel of substantially uniform thickness having circumferentially spaced portions adapted to engage the bottom of the groove, circumferentially spaced portions located between said first mentioned spaced portions and engaging the inner peripheries of said rails, and circumferentially spaced portions extending out-

wardly from only said first mentioned spaced portions and projecting between said rails, and having parallel side edges engaging the facing sides of said rails to space the latter apart at a fixed axial distance thereon.

2. A spacer-expander for piston ring structure having thin, split rails having parallel sides axially spaced apart with their outer peripheries adapted to engage a cylinder wall, which comprises a band-like spring member of polygonal-like shape, the sides of which are adapted to seat upon the bottom of a ring groove, hump-like spring portions connecting said sides at their ends and adapted to engage the inner peripheries of the rails to radially expand the same, and other portions projecting radially outwardly from said sides farther than said hump-like connecting portions, said other portions being adapted to extend between and engage said rails to space said rails axially apart a fixed distance.

3. A spacer-expander for piston ring structure having thin, split rails with substantially parallel facing sides and axially spaced apart with their outer peripheries adapted to engage a cylinder wall, which comprises a band-like spring member of polygonal-like shape, the sides of which are adapted to seat upon the bottom of a ring groove, hump-like spring portions connecting said sides at their ends and adapted to engage the inner peripheries of the rails to radially expand the same, and other portions intermediate said hump-like spring portions projecting outwardly from said sides and having parallel side edges adapted to extend between and engage the facing sides of the rails to space them apart axially a fixed distance.

4. A spacer-expander for piston ring structure having thin, split rails axially spaced apart with their outer peripheries adapted to engage a cylinder wall, which comprises a one-piece polygonally shaped spring member having side portions joined together at their ends by rounded hump-like portions, said side and hump-like portions being of substantially the axial width of the ring groove in which said spacer-expander is to be used with the hump portions adapted to engage the inner peripheries of the ring rails to radially expand the same, and other portions of an axial width substantially equal to the normal axial spacing of the ring rails struck from said side portions and adapted to extend between and engage the ring rails to space said ring rails apart axially.

5. A spacer-expander for use with a pair of piston ring rails to space said rails axially apart and to radially expand said rails comprising: a thin flat steel ribbon bent to generally polygonal form to provide circumferentially spaced side portions connected by hump portions, said side portions being adapted to engage the bottom of a ring groove and said hump portions being adapted to engage the inner periphery of said rails, said side portions having a part thereof struck out to form a rail-spacing portion, and said rail-spacing portions extending radially outwardly farther than said hump portions and being adapted to extend between said rails to axially space said rails apart.

6. A spacer-expander for use with a pair of piston ring rails to space said rails axially apart and to radially expand said rails comprising: a thin flat steel ribbon bent to generally polygonal form to provide circumferentially spaced side portions connected by hump portions, said side portions being adapted to engage the bottom of

a ring groove and said hump portions having crests adapted to engage the inner periphery of said rails, each of said side portions having an outwardly bowed portion extending therefrom and adapted to serve as rail-spacing portions, and the crests of said outwardly bowed portions extending radially outwardly farther than the crests of said hump portions.

7. A multi-piece piston oil control ring comprising a coaxial assembly of a pair of substantially flat relatively thin annular cylinder wall engaging ring members having spaced ends permitting radial expansion and contraction of the members, and an annular sinuous metal expander member mounted interiorly of said ring

members having inwardly extending undulated portions for engaging the bottom of the ring groove and outwardly extending undulated portions for engaging the inner periphery of said ring members and being formed with spacing elements projecting outwardly from said expander member at the inwardly extending undulated portions thereof, said outwardly projecting spacing elements engaging between said rings for holding the same in spaced apart substantially parallel relation, the forming of said outwardly projecting spacing elements leaving openings through said expander at said spacing elements for passage of oil.
